Primary Examiner — Keli L Hill*Assistant Examiner* — Harold E Blackwell, II(74) *Attorney, Agent, or Firm* — Leason Ellis LLP(57) **CLAIM**

The ornamental design for a watering reel, as shown and described.

DESCRIPTION

FIG. 1 is a rear-left perspective view of my watering reel according to my new design;

FIG. 2 is a front view thereof;

FIG. 3 is a rear view thereof;

FIG. 4 is right-side view thereof;

FIG. 5 is a left-side view thereof;

FIG. 6 is a top plan view thereof; and,

FIG. 7 is a bottom plan view thereof.

The broken lines depict portions of the watering reel in which the design is embodied that form no part of the claimed design.
